[57] CLAIM

The ornamental design for a retractable T-hook parts rack, as shown and described.

DESCRIPTION

FIG. 1 is a front perspective view of a retractable T-hook parts rack according to my new design;

FIG. 2 is a front perspective view thereof showing the rack partially extended;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front elevational view thereof; and,

FIG. 8 is a rear elevational view thereof.

Portions of the design depicted in broken line are for illustrative purposes only, and form no part of the claimed design.
